UNITED STATES PATENT OFFICE.

JOHN W. KING, OF CABARTON, IDAHO.

SHOE-SOLE PROTECTOR.

Application filed March 14, 1923. Serial No. 625,037.

To all whom it may concern:

Be it known that I, JOHN W. KING, a citizen of the United States, residing at Cabarton, in the county of Valley and State 5 of Idaho, have invented a new and useful Shoe-Sole Protector, of which the following is a specification.

This invention relates to shoe sole protectors and more particularly to detachable 10 metal soles such as are used by lumber jacks and the like.

The object of the invention is to provide a device of this character adjustable to fit 15 shoes of different sizes and which may be quickly applied and removed.

Another object is to provide a sole of this character equipped with anti-slipping devices.

With the foregoing and other objects in 20 view which will appear as the description proceeds, the invention resides in the combination and arrangement of parts and in the details of construction hereinafter described and claimed, it being understood that 25 changes in the precise embodiment of the invention herein disclosed may be made within the scope of what is claimed without departing from the spirit of the invention.

In the accompanying drawings:

30 Figure 1 represents a side elevation of a shoe protector constructed in accordance with this invention.

Fig. 2 is a bottom plan view thereof, and

Fig. 3 is a transverse section taken on the 35 line 3—3 of Fig. 2.

In the embodiment illustrated, the protector 1 constituting this invention comprises a metal sole 2 preferably composed of sheet steel and to the rear end of which is hinged- 40 ly connected a shank portion 3 which carries a skeleton heel 10. This shank portion 3 is composed of telescopically engaged longitudinally adjustable sections 4 and 5 arranged inlapping relation, the lower section 45 5 having inturned side flanges 6 to form guides in which the section 4 slides. The inner section 4 is hingedly connected by a knuckle 7 to the rear end of the sole 2. These sections 4 and 5 are provided with 50 registering apertures 4^a and 5^a designed to receive connecting bolts 7 which are here shown provided at their lower or projecting ends with spurs 8 which form calks to assist in preventing slipping of the foot of the 55 wearer. Any desired number of apertures

may be provided, two series being here shown those in each being spaced longitudinally from each other to provide for the longitudinal adjustment of the shank members to vary the length of the protector to 60 adapt it to fit shoes of different sizes.

The lower section 5 is provided with a rearwardly extending U-shaped loop or metal strap 9 which is designed to extend around the heel of the shoe and is here 65 shown provided with a leather lining or counter 11 which is riveted or otherwise secured to the strap 9. This strap 9 is preferably provided along its lower edge with a plurality of depending spurs 12 to cooperate 70 with the cork and spurs carried by the sole to prevent slipping.

A leather strap 13 is secured to the counter 11 at the front portion thereof, being made in sections and connected by a buckle 14 to 75 adjustably connect the heel of the protector around the ankle of the wearer.

The sole portion 2 of the protector is here shown provided with transversely extending metal strips 15 and 16 arranged across the 80 bottom of the sole in longitudinally spaced relation and secured thereto by riveting or otherwise. These strips project at their ends beyond the side edges of the sole 2 and the foremost strip 16 is shown equipped 85 with strap receiving openings 17 in its projecting ends with which is connected a strap 18 adapted to extend over the front portion of the wearer's foot and is secured by a buckle 19. A longitudinally extending toe 90 strap 20 is connected with an apertured lug 21 fixed to the front end of the sole and at its rear end is longitudinally slit as shown at 22 for the reception of the cross strap 18. These toe receiving straps may be used 95 if desired, or a toe cap may be substituted therefor.

An arcuate metal strip 23 is shown arranged around the toe portion of the sole 2 on its lower face and secured thereto by 100 riveting or otherwise and the apertured lug 21 is here shown made integral therewith although it need not necessarily be so made.

This strip 23 is provided with a plurality 105 of calks or spurs 24. The strips 15 and 16 are also equipped with similar calks 25 any desired number of which may be employed and if desired, the body of the sole may have outstruck spurs 26 any desired number 110

of which may be used, three being here shown formed at the front end of the sole.

The shank section 5 is provided at its rear edge with a breast portion 27 extending downwardly at right angles and which is adapted to bear against the breast of the shoe heel. This portion 29 is here shown serrated.

The hinged connection of the sole and shank portion of the protector provides for the bending of the sole in walking. This protector may be used by mountain climbers, sportsmen and others, and by removing the two screws or bolts 7 and adjusting the shank of the shoe by sliding the heel backward, the protector may be adapted to fit shoes of different sizes.

Various changes in the form, shape and other details of construction may be made without departing from the spirit of the invention.

I claim:—

A shoe protector comprising a metal sole, a heel encircling strap, a plate carried by the front end of said strap and, provided along its side edges with inturned flanges, another plate hingedly connected with the rear end of said sole and mounted to slide in said flanges, said plates having a plurality of longitudinally spaced registering apertures, fastening elements extending through said apertures to connect the plates in adjusted position, and means for holding the protector in engagement with the foot of the wearer.

In testimony that I claim the foregoing as my own, I have hereto affixed my signature in the presence of two witnesses.

JOHN W. KING.
